UNITED STATES PATENT OFFICE.

ARTHUR J. DAANE, OF CHICAGO, ILLINOIS, ASSIGNOR TO THE ACME PRINTING APPLIANCE CO., OF CHICAGO, ILLINOIS.

VIBRATING ROLLER.

Application filed July 31, 1922. Serial No. 578,546.

To all whom it may concern:

Be it known that I, ARTHUR J. DAANE, a citizen of the United States, residing at Chicago, in the county of Cook and State 5 of Illinois, have invented a certain new and useful Improvement in Vibrating Rollers, of which the following is a full, clear, concise, and exact description, reference being had to the accompanying drawings, forming 10 a part of this specification.

The invention relates to ink distributing rollers or what is commonly known in the printing art as a vibrator roller employed in conjunction with the ordinary printing 15 rolls of a printing press to cause the even distribution of the ink thereon and upon the type carried by the press.

The invention has among its objects the provision of a construction capable of association with a plurality of independent inking roll supports which travel towards and 20 away from the type to be inked.

It is an additional object of the invention to provide a construction capable of association 25 with the above referred to independent inking roll supports which will permit these elements to be separated or moved with relation to each other without permitting the accidental disassociation of the ink distributing roll and the inking rolls of the 30 press, during the travel of the inking rollers.

It is another object of the invention to provide a structure whereby the distributing 35 roller is removably held with respect to the other elements of the press without necessitating the addition of elements to the press to accomplish the desired end.

It is a feature of the invention to provide 40 a construction which may be cooperatively arranged with respect to certain portions of the inking roll frame and particularly that portion of the inking roll frame in which the shafts of the inking rollers are mounted, and to provide the structure with means engageable by a locking pin, said pin being ordinarily employed for locking the inking rollers to the inking roll frame.

It is an additional object of the invention 45 to resiliently secure the distributing roller to the means whereby the distributing roller is mounted with respect to the printing roller frame to thereby resiliently hold the ink distributor roller with relation to the

inking roll frame and in proper contact 55 with the inking rollers the latter of which assume various relative positions during their travel toward and away from the type to be inked, and to permit the association and disconnection of the distributor roll 60 with relation to this frame.

In addition to the above enumerated objects, it is an additional object to provide a portion of the ink distributing roll structure with a holding pin which is movable 65 therewith and movable with respect thereto, to permit the association and release of the distributor roll structure relatively to said inking roller frames, and to properly hold the distributor roller against accidental disconnection 70 from said frames during the actuation of the distributor roller.

In the particular arrangement illustrated the ink distributor roll is arranged to reciprocate lengthwise of a shaft upon which 75 the distributing roller is mounted. The opposite ends of the distributor roller shaft each has a bracket secured thereto, which is movable transversely to the length of the shaft. This bracket has one end thereof 80 provided with a transversely arranged pivoted element the opposite ends of which are designed to cooperate with the elements in which the inking rollers of the press are journaled, and is capable of association with 85 either a single or a plurality of independent inking roll supports.

In the structure of the printing press illustrated in the drawings, the inking rollers are carried by two independently movable 90 elements which are reciprocably mounted with respect to a swinging frame of the press, which when actuated causes the inking rollers to travel towards and away from the platen of the press and type 95 carried by the press.

One of these independently movable elements to which the inking rollers are attached will hereinafter be referred to as a hook and the other as the saddle.

The saddle in most types of printing presses such as illustrated is designed to carry a pair of inking rollers. The hook having secured thereto a single inking roller, the latter being arranged with respect to the inking roller of the saddle so that it precedes the former as said inking rollers travel towards the type to be

inked. The distributor or vibrator roller is in one arrangement designed to be positioned to cooperate with the inking roll carried by the hook and the adjacent inking roller carried by the saddle. In another embodiment of the invention, the vibrator roll is permitted to be arranged between inking rollers carried by the saddle.

In still another embodiment of the invention, the structure whereby the distributing roller is held with respect to the hook and saddle, is designed to directly engage a part of the hook and a part of the saddle and to move to limited extent with respect thereto, to compensate for variations of distance between the hook and saddle as they travel toward and away from the type carried by the press.

The invention will be described in detail and more readily understood when read in conjunction with the accompanying drawings which illustrate various structures whereby the invention may be accomplished, it being therefore obvious that the invention is susceptible to changes and modifications without departing from the spirit of the appended claims forming a part hereof.

In the drawings, Figure 1 is a side elevation of a portion of a printing press showing one embodiment of the invention applied thereto.

Figure 2 is an elevation of a portion of the structure shown in Figure 1, illustrating the vibrator roll associated with the hook and saddle of a printing press.

Figure 3 is a top plan view of the structure shown in Figure 2 the hook and saddle being eliminated.

Figure 4 is a front view of a distributor roll having the structure illustrated in Figures 2 and 3, applied thereto.

Figure 5 is an end view of a modified arrangement which may be resorted to for engaging the hook and saddle.

Figure 6 is a plan view of a portion of the structure illustrated in Figure 5.

Figure 7 is another modified arrangement which may be employed for engaging the hook and saddle to hold the vibrator roll with respect to the press.

Figure 8 is an end portion of a structure which may be employed for holding the vibrator roll with respect to the saddle of the press embodying a means provided for the reception of a locking pin for locking the vibrator roll and its associated devices with respect to the saddle.

Figure 9 is a top plan view of the structure illustrated in Figure 8.

Figure 10 is a section taken on line 10—10 of Figure 8.

Figure 11 is a top plan view of the structure similar to that illustrated in Figure 8, showing a modified arrangement which may be resorted to.

Figure 12 is a section taken on line 12—12 of Figure 11.

Figure 13 is a top plan view of the structure shown in Figure 7.

Figures 14 and 15 are end elevations of structures similar to that disclosed in Figure 8.

Figure 16 is a view partially in section illustrating a locking pin construction which may be employed for holding the vibrator roll with respect to the saddle.

Figures 17 and 18 are end elevations of still other modifications which may be employed to accomplish the invention.

Figures 19 and 20 are sectional views of certain details of construction employed in the structure.

The structure illustrated in Figures 1 to 5, 7, 17 and 18 illustrate means operable with both the hook and saddle to cooperatively hold the vibrator roll with respect to the inking rollers carried by the hook and saddle.

The particular vibrator roll structure illustrated in the drawings contemplates the use of the roller 21 which is mounted to reciprocate with respect to the shaft 22, the reciprocation being caused by the rotation of the vibrator roll 21 with respect to the threaded portion 23, with which the roller is in engagement.

A bracket 24 is arranged adjacent the opposite ends of the shaft 22, and each of these brackets is provided with an inwardly projecting portion 25 which is apertured at 26 for the reception of a pin 27 one of which is arranged and secured to the opposite ends of the vibrating shaft 22.

The opposite ends of the vibrator shaft extend through a slotted aperture 28 provided in the bracket 24 and a plate 29 is secured in any suitable manner to the ends of the shaft 22. The side edges of this plate 29 are notched as indicated at 30 for the reception of the edges of the slot 28. This arrangement permits the shaft 22 to be moved lengthwise of the slot 28 and prevents the accidental separation of these portions at this point.

Coiled springs 31 are employed and arranged upon the pins 27, these springs react between the projection 25 and the ends of the shaft 22, and resiliently retain the ends of the shafts adjacent the lowermost end of the slots 28.

The bracket 24 extends a suitable distance below the end of the shaft 22 and the slot provided therein and has pivotally secured thereto the swinging element generally designated 32, which is clearly shown in Figures 2 and 3.

This swinging element 32 is pivotally secured to the bracket 24 by means of the pivot pin 33, and extends a suitable distance upon opposite sides of the pivot thereof and has

its extremities provided with the inwardly extending projections 34 and 35 which respectively cooperate with suitable portions of the hook 36 of the inking roller 37 and the saddle 38 of the inking roller 39.

These projections 34 and 35 of this embodiment of the invention are designed to enter the recesses in the hook 36 and the saddle 38 provided for the reception of the ends of the shafts such as 40 and 41 of the inking rollers 37 and 39.

In the particular structure illustrated in Figures 2 and 3 the projections 34 and 35 are shown as engaging the ends of the shafts 40 and 41. This particular arrangement need not be adhered to, to accomplish the invention, as it will be apparent by referring to the structure illustrated in Figure 5 that the pivoted element may engage directly a suitable portion of both the hook and saddle.

To cooperatively associate the structure with the press, the shaft 22 of the vibrator roll will be moved with respect to the bracket 24 so as to compress the coiled springs 31.

The extension 35 will then be passed between the hook 36 and the adjacent end of the saddle 38 and arranged below the lowermost face of the saddle and then moved endwise and upwardly of the saddle, which positions the projections 34 and 35 adjacent the recesses in which the ends of the shafts 40 and 41 are confined.

Upon the release of the pressure applied to the coiled spring 31 the parts will assume the position shown in Figure 2 with the vibrator roll 21 arranged between the inking rollers 37 and 39 and the extensions 34 and 35 in contact with the respective shafts of the inking rollers, in which position the parts will be retained by the coiled springs 31.

In some instances it will be found that these shafts 40 and 41 project a slight distance beyond the outermost face of the hook and saddle, therefore some provision must be made to permit the innermost face of the pivoted element 32 to clear the end of a shaft such as 40 to permit the application of the structure to the hook and saddle.

To accomplish this, a structure such as illustrated in Figures 19 and 20 may be resorted to. The structure illustrated in Figure 19 contemplates recessing the pin 27 as indicated at 42 which will allow the bracket 24 to cant, the connection between the member 29 and the shaft acting as a pivot.

The structure shown in Figure 20 may be also employed which contemplates providing the bracket 24 with a notch 43 arranged adjacent the uppermost extremity of the slot 28, provided in the bracket. In this instance the aperture 26 provided in the inwardly projecting portion 25 of the bracket, will be of a relatively larger dimension than

the pin 27 which will cooperate with the notch 43 to permit the bracket 24 to be tilted in the manner illustrated in Figure 20.

The structure illustrated in Figures 19 and 20 will readily permit the pivoted element 32 to be moved to clear the projecting ends of the shafts 40 and 41 of the inking rollers 37 and 39.

In Figures 5, 6 and 7 other swinging elements are illustrated and respectively designated 44 and 44^a. These swinging elements 44 and 44^a are designed to directly engage the hook and saddle of the inking roll trucks and also permit the elements 44 and 44^a to move with respect to the hook and saddle lengthwise of said elements.

This endwise movement is necessitated because of the relative movement between the hook and saddle as they move from the platen of the printing press to the type and back again, and travel over the various faces of the track arranged upon opposite sides of the platen and type to be inked.

In the structure illustrated in Figures 5 and 6 the pivoted element 44 is provided with the inwardly projecting ledges 45 and 46.

In Fig. 6 the ledge 46 is designed to provide the upwardly extending projections 47 and 48 between the latter of which an end of the saddle such as 38^a is adapted to be arranged. The inwardly projecting ledges 45 and 46 respectively contact with the hook 36^a and saddle 38^a and permit the element 44 to slide endwise relatively to the hook and saddle, for the purpose above referred to and the upwardly extending portions 47 and 48 limit this endwise movement of the swinging element and hook and saddle.

The upward extension 48 of the pivoted element 44 is provided with a slot 49 to permit the introduction of the holding pin ordinarily employed for holding the inking rollers carried by the saddle with relation to the saddle.

Another modified arrangement which may be employed is illustrated in Figure 17, which contemplates the utilization of a pivoted element constructed in accordance with that illustrated in Figure 2, differing however, in that the pivoted element is provided with an extension 50 which engages the end of the hook in which one of the inking rollers is mounted and permits the hook and roller to move endwise with respect to the pivoted element and the saddle in which the other inking rollers are arranged.

In the structure shown in Figure 7 the inwardly projecting portion 45^a is provided with a downwardly projecting portion 51 and the inwardly projecting portion 46^a is provided with a single upwardly extending portion 52.

The two portions 51 and 52 are provided to cooperatively engage the hook and the

saddle to limit the movement of the pivoted element with respect to the hook and saddle.

In Figures 8, 9, 11, 14 and 15 other modifications are illustrated.

5 These structures are designed to be associated with the saddle of the printing press to cooperatively hold a distributing roller with relation to the inking rollers carried by the saddle of the press.

10 The arrangement in Figs. 8 and 9 contemplates the use of a bracket 53, a vibrator roll shaft 54, a spring 55, pivoted element 56 and other elements similar to those referred to in the structures previously described,

15 differing however in that the pivoted element 56, engages both of the shafts 57 and 58 of the inking rollers carried by the saddle.

20 The pivoted element in this instance is provided with the inwardly extending portions 59 and 60 the terminations of which are bent downwardly as indicated at 61 and 62. These downward extensions 61 and 62 are provided to cooperate with the removable pin 63, which is ordinarily employed to guard against the accidental disassociation of the shafts 57 and 58 and the saddle.

25 The structure shown in Figure 11 is similar to that shown in Figures 8 and 9 differing however in that the downward projections of the extensions 59 and 60 are constructed as illustrated in Figure 12 to receive the holding pin 63.

30 In this last named structure the extremities of these inward projections are hook-shaped as indicated at 64 to receive the holding pin.

35 The arrangements illustrated in Figures 14 and 15, also contemplate the use of a pivoted element and a bracket to which the pivoted element is secured. The structure illustrated in Figure 14 is particularly designed to compensate for the projecting end of a pin employed to hold the saddle and the swinging element in associated relation.

40 To compensate for this projecting portion of the pin, the pivoted element is cut-away as indicated at 65, and the pivot 66 whereby the bracket and the swinging element are secured together is arranged above the pin.

45 The structure illustrated in Figure 15 contemplates providing the bracket which carries the vibrator roll and other elements of the structure, with an aperture 67 and arranging the pivot 68 of the pivoted element 69 below the pin 70. The head of the pin 70 being arranged in the aperture, it being of course understood that this arrangement 50 may employ the structure shown in Figures 19 and 20 which permits the bracket such as 24 to be moved with respect to the pin and thereby allow its association in the manner illustrated.

55 In Figure 16 is illustrated what might be termed a pull-stop which is employed to

cooperate with the bracket 28 to hold the vibrator shaft against lateral movement with respect to the saddle yet will permit the vibrator shaft to move with respect to the saddle, transversely of the saddle preventing the possibility of accidental separation of the vibrator shaft and its associated elements and the saddle.

60 This pull-stop is designed to be resiliently held in its extended condition and to be retracted or moved with respect to the vibrator shaft to permit the association and disassociation of the structure from the printing press.

65 The projecting end of the pull-stop pin 80 is of a length greater than the movement permitted between the bracket and the shaft of the vibrator, and will thus necessitate additional movement to be imparted to the pin in order to disconnect the structure 70 from the press. The pull-stop 71 is passed through an aperture 72 in the vibrator shaft and extends upwardly through a housing 73 which is formed of the material of which 75 the element 29 is formed.

80 The pin 71 is provided with a shoulder 74 and a coiled spring 75 is arranged upon the pin. This spring reacts between the shoulder 74 and one end of the housing 85 which tends to maintain the pin in the position shown in Figure 16 yet will permit the pin to be retracted or moved with relation to the shaft of the vibrator roll to allow it to clear the saddle when it is desired to remove the vibrator roll and its associated structure from the press. It is understood 90 that the vibrator shaft is at this time arranged adjacent the uppermost extremity of the slot 28 of the bracket 24.

95 In Figure 18 is illustrated a combination 100 of pivoted elements, brackets, and distributor rollers which permits a distributor roller to be arranged between the inking roller carried by the hook and the adjacent inking roller carried by the saddle, and another distributor roller to be positioned between both of the inking rollers carried by the saddle.

105 This structure contemplates the use of 110 two pivoted elements 76 and 77 which are held in pivotal relation to each other at 78.

110 The pivoted element 77 is provided with 115 inwardly projecting portions 79 and 80 and the pivoted element 76 is provided with an inwardly projecting portion 81. These inwardly projecting portions are similar to those previously described and perform the same function.

120 The pivoted elements 76 and 77 are respectively secured to the brackets 82 and 83 125 which are slotted as previously explained to accept the shafts 84 and 85 of the distributing rollers 86 and 87.

130 From the foregoing description, it is evident that an arrangement is provided which

may be cooperatively arranged with respect to independent elements such as the hook and saddle of a printing press, which are movable with respect to each other, as they travel towards and away from the type to be inked.

It is further manifest that the structure will be maintained in associated relation during its travel towards and away from the type to be inked and that a structure is provided which may be readily associated and disconnected from the press when this is found necessary or desirable.

It is further evident that a structure is provided which may be associated and secured in cooperative relation to the saddle so that a distributing roller may be arranged between the inking rollers carried by the saddle.

20 It is also manifest that an arrangement is provided whereby an inking roll may be arranged and cooperatively held in associated relation to the inking roll carried by the hook and the inking rollers carried by the saddle, and that all of said structures are resiliently and releasably held with respect to the press.

It is obvious that the various structures illustrated may be rearranged and combined with each other to provide various combinations.

Having thus described the invention what I claim and desire to cover by Letters Patent is:

35 1. In a support for an ink distributing roller for printing presses, said press having an inking roller hook and saddle, said ink distributing roller being permitted to be arranged between inking rollers carried by the respective inking roller hook and saddle and means whereby said distributing roller is held in associated relation to said inking rollers carried by said inking roller hook and saddle, said means including a means 40 which extends parallel to and between the inking roller hook and saddle, said distributing roller being permitted to be associated with and removed from the hook and saddle while the hook and saddle are in associated 45 relation with the inking rollers.

50 2. In a support for an ink distributing roller for printing presses, said press having an independently movable inking roller hook and saddle, said ink distributing roller being permitted to be arranged between inking rollers carried by the respective inking roller hook and saddle and means whereby said distributing roller is held in associated relation to said inking rollers carried by said inking roller hook and saddle, said means including a pivoted element which is arranged parallel to and extends between the inking roller hook and saddle, said distributing roller being permitted to be associated 55 and removed from the hook and saddle while

the same are in associated relation with the inking rollers.

3. In a support for an ink distributing roller for printing presses, said press having an independently movable inking roller hook 70 and saddle, said ink distributing roller being resiliently mounted and being permitted to be arranged between inking rollers carried by the inking roller hook and saddle and means whereby said distributing roller is held in associated relation to said inking rollers carried by said inking roller hook and saddle, said means including a means which extends from the hook to the saddle and permitting the distributing roller to be attached 75 and removed from the hook and saddle while the same are in associated relation with the inking rollers.

4. In a support for an ink distributing roller for printing presses, said press having an independently movable inking roller hook and saddle, said ink distributing roller being resiliently mounted and being permitted to be arranged between inking rollers carried by the inking roller hook and saddle and means whereby said distributing roller is 80 held in associated relation to said inking rollers carried by said hook and saddle, said means including a pivoted means which extends from the hook and saddle and permits the distributing roller to be attached and removed from the hook and saddle while same 85 are in associated relation with the inking rollers.

5. In a support for an ink distributing roller for printing presses, said press having an independently movable inking roller hook and saddle, said ink distributing roller being permitted to be arranged between inking rollers carried by the respective inking roller hook and saddle and means whereby said distributing roller is held in associated relation to said inking rollers carried by said inking roller hook and saddle, said means including a means which extends from the hook to the saddle and permits the distributing roller to be attached and removed from the hook and saddle while same are in associated relation with the inking rollers, and a resilient element 100 acting upon said means.

6. In a support for an ink distributing roller for printing presses, said press having independently movable inking roller carriages, said ink distributing roller being permitted to be arranged between inking rollers carried by the respective inking roller carriages and means whereby said distributing roller is held in associated relation to said inking rollers carried by said inking roller carriages, said means including a means which extends from one inking roller carriage to the other, having a laterally extending portion which extends inwardly towards the carriages.

7. In a support for an ink distributing roller for printing presses, said press having independently movable inking roller carriages, said ink distributing roller being permitted to be arranged between inking rollers carried by the respective inking roller carriages and means whereby said distributing roller is held in associated relation to said inking rollers carried by said inking roller carriages, said means including a pivoted means which extends from one inking roller carriage to the other, having a laterally extending portion which extends inwardly towards the carriages.
15. 8. In a support for an ink distributing roller for printing presses, said press having independently movable inking roller carriages, said ink distributing roller being resiliently mounted and being permitted to be arranged between inking rollers carried by the respective inking roller carriages and means whereby said distributing roller is held in associated relation to said inking rollers carried by said inking roller carriages, said means including a means which extends from one inking roller carriage to the other, having a laterally extending portion which extends inwardly towards the carriages.
20. 9. In a support for an ink distributing roller for printing presses, said press having independently movable inking roller carriages, said ink distributing roller being permitted to be arranged between inking rollers carried by the respective inking roller carriages and means whereby said distributing roller is held in associated relation to said inking rollers carried by said inking roller carriages, said means including a means which extends from one inking roller carriage to the other, having a laterally extending portion which extends inwardly towards the carriages.
25. 10. In a support for an ink distributing roller for printing presses, said press having a hook and saddle to which inking rollers are attached, the combination of means whereby said roller may be associated and held with respect to said hook and saddle of the inking rollers of the press, said means including an element which is engageable with the shafts of the inking rollers and permits the association and removal of the distributing roller while the inking rollers are in associated relation with said hook and saddle.
30. 11. In a support for an ink distributing roller for printing presses, the combination of means whereby said roller may be associated with frames in which the inking rollers of the printing press are mounted said means including portions which are permitted to be arranged at a side face of and in those portions of said frames in which the shafts of the inking rollers are mounted while said inking rollers are associated with said frames.
35. 12. In a support for an ink distributing roller for printing presses, the combination of means whereby said roller may be associated with frames in which the inking rollers of the printing press are mounted said means including portions which are permitted to be arranged in those portions of said frames in which the shafts of the inking rollers are mounted while said shafts are in associated relation and a member pivoted to said portion, said last mentioned member having the distributing roller secured thereto.
40. 13. In a support for an ink distributing roller for printing presses, the combination of means whereby said roller may be associated with a frame in which the inking rollers of the printing press are mounted said means including a portion, to which said distributing roller is attached and an element pivotally secured to said portion, said element being extended in opposite directions from the pivot thereof and said extensions having portions which project into openings provided in the frame in which the inking rollers are mounted.
45. 14. In a support for an ink distributing roller for printing presses, the combination of pivoted means whereby said roller may be associated with a frame in which the inking rollers of the printing press are mounted said means including oppositely extending portions which are adapted to be arranged in that portion of said frame in which the shafts of the inking rollers are mounted, and said distributing roller being mounted for reciprocation transversely to the axis of the distributing roller.
50. 15. In a support for an ink distributing roller for printing presses the combination of a shaft upon which said roller is mounted, a member to which said shaft is connected, said shaft being mounted to reciprocate with respect to said member, an element pivotally secured to said member, said last mentioned member having portions which extend in opposite directions from the pivot of said member and being provided to enter openings in which inking rollers of the press are mounted.
55. 16. In a support for an ink distributing roller for printing presses, said press having independently movable inking roller carriages each having a hook shaped portion, said ink distributing roller being permitted to be arranged between inking rollers carried by the respective inking roller carriages and means whereby said distributing roller is held in associated relation to said inking rollers carried by said inking roller carriages, said means including a means which extends from one inking roller car-

riage to the other, and having means which enter the opening of the hook shaped portion of the respective inking roller carriages.

- 5 17. In a support for an ink distributing roller for printing presses, said press having independently movable inking roller carriages, said ink distributing roller being permitted to be arranged between inking 45 rollers carried by the respective inking 10 roller carriages and means whereby said distributing roller is held in associated relation to said inking rollers carried by said inking roller frames, said means including 15 a means which extends from one inking roller frame to the other, and a resilient element acting upon said means, permitting one inking roller frame to move with respect to the other.
- 20 18. In a support for an ink distributing roller for printing presses, said press having independently movable inking roller carriages, said ink distributing roller being permitted to be arranged between inking 25 rollers carried by the respective inking roller carriages and means whereby said distributing roller is held in associated relation to said inking roller frames, said means including 30 a means which extends from one inking roller frame to the other, having a laterally extending portion which extends inwardly towards the carriages, and permits one inking roller frame to move with respect to the other.
- 35 19. In a support for an ink distributing roller for printing presses, said press having independently movable inking roller carriages each having a hook shaped portion, said ink distributing roller being permitted to be arranged between inking rollers carried by the respective inking roller carriages and said support including pivoted

means whereby said distributing roller is held in associated relation to said inking 45 rollers carried by said inking roller carriages, and which extends from one inking roller carriage to the other, and having means which enter the opening of each hook shaped portion of the respective inking 50 roller carriages, said pivoted means permitting one inking roller carriage to move with respect to the other.

5 20. In a support for an ink distributing roller for printing presses, said press having independently movable inking roller carriages, said ink distributing roller being permitted to be arranged between inking 55 rollers carried by the respective inking roller carriages and said support including 60 means whereby said distributing roller is held in associated relation to said inking rollers carried by said inking roller carriages, which extends from one inking roller carriage to the other, having a laterally 65 extending portion which extends inwardly towards the carriages, and a resilient element acting upon said means, permitting one inking roller carriage to move with respect to the other.

70 21. In a support for an ink distributing roller for printing presses, the combination of means whereby said roller may be associated with a frame in which the inking rollers of the press are mounted, said means 75 including an element with respect to which the distributing roller is resiliently mounted and having portions which are extended in opposite directions from the distributing roller and project into openings provided 80 in the frame in which the inking rollers are mounted.

In witness whereof, I hereunto subscribe my name this 30th day of June A. D., 1922.

ARTHUR J. DAANE.
